(57) **CLAIM**

The ornamental design for a food container, as shown.

DESCRIPTION

FIG. 1 is a top plan view of a closed food container showing my new design.

FIG. 2 is a bottom plan view thereof.

FIG. 3 is a perspective view showing the rear and left sides thereof

FIG. 4 is a perspective view showing the front and right sides thereof.

FIG. 5 is a perspective view of my food container in a partially opened setting.

FIG. 6 is a perspective view of my food container in a completely opened setting.

FIG. 7 is a front elevational view of the entirely opened food container; and,

FIG. 8 is a rear elevational view of the entirely opened food container.
